COMBINATION DRAFTING INSTRUMENT

Edwin G. Brockman, 300 Calle Mayor,
Redondo Beach, Calif.

Filed Sept. 2, 1960, Ser. No. 61,995

Term of patent 7 years

(Cl. D52—6)

FIG. 1

FIG. 2

FIG. 6

FIG. 3

FIG. 4

FIG. 5

FIGURE 1 is a top plan view of a combination drafting instrument showing my new design;

FIGURE 2 is a left end elevational view of FIGURE 1;
FIGURE 3 is a right end elevational view of FIGURE 1;

FIGURE 4 is a top edge elevational view of FIGURE 1;

FIGURE 5 is a bottom edge view thereof; and

FIGURE 6 is a vertical section taken on line 6—6 of FIGURE 1.

The opposite side of FIGURE 1 is plain in appearance, except at the bottom as indicated in FIG. 6.

I claim:

The ornamental design for a combination drafting instrument, as shown and described.
